ROUNDING MACHINE

James P. Fredericksen, Quincy, Mass., assignor to
 United Shoe Machinery Corporation, Flemington, N. J., a corporation of New Jersey

Application July 21, 1942, Serial No. 451,745

24 Claims. (Cl. 12—18)

This invention relates to machines for rounding or cutting work-pieces to the desired contour, it being especially applicable to apparatus for rough-rounding soles attached to shoe-uppers.

In rounding machines of the type disclosed in Letters Patent of the United States No. 1,030,606, Perry, June 25, 1912, the work is advanced in successive steps to receive the action of a reciprocatory chopping knife, by outer and inner members which have a relative movement of approach to grasp the sole-edge. They then oscillate together to feed the work forward, after which they separate to release said work and swing rearwardly in preparation for the next feeding step. For this rearward travel, only the outer member has a movement of separation, being carried by a four-motion actuating mechanism to a point opposite the chopping knife to furnish for it a cutting abutment. With the knife and its associated sticker-point in the work at the termination of the cutting stroke, the inner member returns to its initial position. At this time, the planes in which the work-engaging faces of the members oscillate are closest to each other, so that the inner may drag upon the surface of the work. Rearward displacement of said work by this contact, which would reduce the effective advance, is resisted by the chopping knife and sticker-point. There may, however, be an insufficient chip or waste-margin to be engaged by the latter, so the retaining effect is not enough to prevent what is commonly termed back-feed. This is especially liable to be present when the sole-edge differs considerably in thickness about the periphery, as in spring-heel-shoes or those with rubber soles. Here, the separation between the feeding members, which is adequate at the thinner portions, will cause them to bind and back-feed at the thicker. Particularly troublesome in this respect is the rounding of crepe-rubber soles, with which, to the considerable variations in thickness, are added the expansibility of the material and its adhesiveness. An object of this invention is to ensure such a separation between the work-feeding members, that the retrograde movement will be prevented, whatever the thickness and character of the work.

To gain the above end, I produce a relative movement of the feeding members which co-operate with the rounding knife through a predetermined distance from the surface of the work, this being accomplished by measuring the thickness of said work and then adding the movement of release to this measured dimension. It is,

therefore, only necessary to decide upon a clearance which will guard against back-feeding engagement, and this will be created between the feeding members and the margin of a sole, regardless of its thickness and expansibility. The means which withdraws one of the feeding members from the work is preferably made effective in the feeding movement of said members. As herein disclosed, this means consists of a coupling device through which the movement of separation or work-release is transmitted, said coupling device being disconnected at the termination of the return movement of the feeding members to permit the work-measuring effect. 10 The time-relation of this release and the point of connection of the coupling device may be made variable. More specifically, the means for grasping and measuring the work includes a spring, while the withdrawing or actuating means for the 15 feeding member may include a cam. The coupling device is preferably furnished by a rack or toothed member and a pawl which engages it, the toothed member being movable by the cam or other actuating means, as through an intermediate lever and gear, and the pawl being carried by the feeding member.

In the accompanying drawings,

Fig. 1 shows in broken side elevation a particular embodiment of my invention, the elements being shown as the bottom-rest approaches the end of its reverse travel;

Fig. 2 is a horizontal section on the line II—II of Fig. 1;

Fig. 3, a fragmentary top plan view, enlarged, 30 of the work-feeding elements when in their extreme rearward positions;

Fig. 4, a partial vertical section on the line IV—IV of Fig. 1;

Fig. 5, a like view showing a portion only of 40 the elements of Fig. 4, these being illustrated as at the beginning of the work-feeding movement; and

Fig. 6 is a fragmentary side elevation, showing the withdrawing mechanism for the bottom-rest after the rest has terminated its reverse travel.

I have chosen to illustrate this invention in connection with the machine of the previously mentioned patent, this being the well known 50 Goodyear Universal Rounding and Channeling Machine—Model E. This apparatus may be employed to rough-round a sole S attached to the bottom of a shoe-upper U, and to simultaneously cut a channel therein. It is the former purpose which is important in the present connec-

tion, and no further consideration will be given to the production of the channel. There is a chopping knife 10 with its sticker-point 11 fixed in a horizontal slide 12, which is in constant reciprocation upon the frame 14 during the operation of the machine. The knife cuts against an abutment furnished by a plate 16, which is movable between spaced side-arms of a guide 17 adapted to enter the crease between the sole and the upper. The plate 16 acts to grasp and advance the work for the rounding operation, having a four-motion feed, its carrier-shaft 18 being reciprocated longitudinally by a groove 20 in the periphery of a cam-cylinder 22 upon a shaft 24 and oscillated by a groove 26 in the inner face of the cam-cylinder. The shaft is constantly driven in the direction of the arrows in Figs. 1 and 4. The work-feeding member co-operating with the plate 16 consists of a block 28 opposite said plate and providing a bottom-rest for the tread-surface of the sole S. This bottom-rest is supported upon a carrier-arm 30 rising from the forward extremity of a sleeve 31 secured to a tubular shaft 32, journaled in bearings 33 and 34 upon the frame 14. The shaft is oscillated to give the work-feeding effect from a groove 35 in the cam-cylinder 22, through a bell-crank-lever 36 and an arm 38 extending from the sleeve 31 and which may travel along a projection 40 from the lever. The bottom-rest is thrust yieldably toward the feed-plate 16 by a tension-spring 42 and a lever 44, acting upon a rod 46 extending into the tubular shaft. The arrangement whereby the bottom-rest yields may be as in Letters Patent of the United States No. 1,955,753, Lawson, April 24, 1934, and allows the feeding means to accommodate itself to soles of different thicknesses. For the entrance of the sole-edge between the feed-plate and the bottom-rest, the latter may be retracted by the actuation of a lever 47 which engages a projection from the sleeve 31.

Considering a single cycle of the feeding and rounding mechanisms described above, and starting with the plate 16 and rest 28 at the right, or as seen in Fig. 3, the plate is positioned outwardly from the rest to the maximum extent. This gives a space which may be increased by actuation of the lever 47 and into which the operator may introduce the sole-edge. The rounding knife 10 is fully withdrawn rearwardly. A sole is located by the operator by engagement of the crease between the upper U and the sole S with the guide 17, the welt or upper margin of the sole-edge being presented to the feed-plate 16 and the tread-surface to the bottom-rest 28. The feed-plate moves in and clamps the work against the bottom-rest, the spring mechanism 42, 44 yielding to equalize the pressure. The plate and rest then swing to the left to feed the work a full step, after which the plate is withdrawn from the rest, which temporarily remains stationary, and moves part way back to the right and inwardly to the plane of its forward feeding travel. It is now opposite the knife 10, which advances with its sticker-point 11 to make a rounding cut against the plate. The knife maintains this position with the sticker-point in the severed margin, while the bottom-rest returns the full distance to the right to its initial position. The knife and plate separate, and the latter moves to the right for the beginning of the succeeding cycle.

As has already been pointed out, the bottom-rest may in its rearward oscillation carry the work with it, so that at least a portion of its effect is lost. The highly expandable and sticky crepe-

rubber offers the worst conditions, and, to eliminate the possibility of back-feed for this and all materials, however variable in thickness, I introduce an additional movement of the feeding members 5 which takes into account the thickness of the work being operated upon. This movement is preferably imparted to the bottom-rest to separate it from the feed-plate, and is initiated from the tread-surface of the sole. Attached to the frame 10, below and at one side of the shaft 32, is a bracket 50, in which is rotatable a pinion 52 oscillated by a bell-crank-lever 53 upon one arm of which is a gear-segment 54 meshing with the pinion. A second arm of the lever has turning upon it a roll 56 lying in a cam-groove 58 in the periphery of the cam-cylinder 22. The side-walls of this groove lie generally in parallel planes at right angles to the axis of rotation, except at 59, where there is a lateral offset which turns the lever 53 abruptly clockwise (Fig. 1), so holds it for a time and then returns it to the normal position. The roll may be differently located along the lever by clamping its mounting in a vertical slot 60. Projecting from the pinion is an arm 61, which 15 may be secured in different angular positions by a slot-and-screw connection 62. The arm extends between pins 64, 64 passing through a horizontal slot 66 at one side of horizontal ways in the frame 14. In the ways, a slide 68 is movable, it carrying 20 the pins 64 and bearing upon its upper side a toothed rack 70. Meshing with the rack-teeth are double pawls 72, 72, staggered to ensure prompt engagement. The pawls are pivoted side by side upon a projection 74 from the sleeve 31, and are urged toward the rack-teeth by their respective leaf-springs 76, 76 attached to a lug 78 upon the sleeve. The rack-engaging points of the pawls are variably limited in the extent of their downward movement by screws 80 threaded through tails 82 and contacting with the under-side of the lug.

During the feeding and return movements of the sleeve 31 with the arm 30 and bottom-rest 28, the relation, of the depth of engagement of the pawls 72 with the teeth 70 to the angle through which said pawls oscillate, is such that the points of the pawls lie between the teeth at all times, save when the bottom-rest in its movement to the right is approaching the initial position from which it starts its opposite, work-feeding travel. At this time, the pawls leave the teeth, so the bottom-rest may be positioned under the influence of the spring 42. As the pawls thus clear the teeth, the cam-offset 59 is just leaving the roll 56 of the lever 53. The operator by movement of the lever 47 draws back the bottom-rest against the force of the spring, introduces the sole-edge between the feed-plate and bottom-rest to an extent determined by the crease-guide 17 and releases the lever. As the bottom-rest reaches the position illustrated in Fig. 3, ready for its feeding advance, the pawls 72 are fully lifted from the teeth 70, as appears in Figs. 5 and 6. Said bottom-rest is thus freed to be carried by the spring 42 into contact with the tread-surface of the sole, at whatever point in the periphery is then presented to it, and holds the welt-side of the edge against the feed-plate. There is thus measured the thickness of the sole at the point engaged. As the bottom-rest and feed-plate begin their forward feeding movement, the pawls have entered between the teeth, these elements being made effective as a coupling device to join the sleeve 31 to the actuating slide 68. The roll 56 is at this time in the main por-

tion of the groove 58, which holds the lever 53 against movement. But just as the cam-groove 35 starts the idle return movement of the bottom-rest, the cam-offset 59 acts upon the roll, swinging the lever clockwise (Fig. 1) and rotating the pinion 52 contraclockwise. The arm 61 is turned to the left, and, by contact with the pin 64 at that side, correspondingly shifts the slide 68. The teeth 70 acting upon the pawls 72 move the sleeve 31 in the same direction, separating the bottom-rest positively from the sole by whatever distance may be desirable to ensure against back-feeding effect upon the work. Figs. 1, 2 and 4 of the drawings illustrate the elements at an intermediate point in the movement of withdrawal. The rest is held in the retracted position until the reverse travel is at the point of completion, and the pawls are raised from the teeth, when the offset passes away from the roll, restoring the slide 68 to its initial position and leaving the bottom-rest free to measure the thickness of the sole at the point which is now presented. It will be seen that, by such an organization, variations in the thickness of the sole-edge are without effect upon the distance through which the bottom-rest is separated from the tread-surface of the sole. This distance may be chosen with reference to preventing undue frictional engagement of the bottom-rest with said surface, while it still is in a position to steady the work against separation from the feed-plate. The chopping knife 10 acts in the usual manner by its successive cuts, to gradually round the sole during its feed to a contour determined by the entrance of the guide 17 into the crease. Adjustment of the roll 56 along the slot 60 in the lever 53 provides for the correct time-relation between reversal of oscillation of the bottom-rest and its withdrawal from the work. By angular adjustment of the arm 61 and consequent variation in the normal position of the slide 68, it may be made certain that, for any range of thickness of sole-edges being operated upon, the pawls 72 will always come into engagement with the rack-teeth 70. The extent of entrance of the pawls between and withdrawal from the teeth is under the control of the screws 80.

Having described my invention, what I claim as new and desire to secure by Letters Patent of the United States is:

1. In a rounding machine, a knife, opposite work-feeding members co-operating with the knife, means for moving the feeding members in opposite directions first to advance the work to receive the action of the knife and then to return them to their initial positions, and means for producing relative movement of the members toward and from each other alternately to grasp the work for feeding and to release it during the return movement, the movement of release being through a predetermined distance from the surface of the work.

2. In a rounding machine, a knife, opposite work-feeding members co-operating with the knife, means for moving the feeding members in opposite directions first to advance the work to receive the action of the knife and then to return them to their initial positions, means for producing relative movement of the members toward and from each other alternately to grasp the work for feeding and to release it during the return movement, the movement of release being through a predetermined distance from the surface of the work, and means arranged to vary the

time-relation between the return movement and the release of the work.

3. In a rounding machine, a knife, opposite work-feeding members co-operating with the knife, means for moving the feeding members in opposite directions first to advance the work to receive the action of the knife and then to return them to their initial positions, means for establishing contact between the members and the work to measure its thickness, and means for moving the members relatively to grasp the work for feeding and to release it, the movement of release being added to the measured thickness.

4. In a rounding machine, a knife, opposite work-feeding members co-operating with the knife, one of said members being yieldable under the influence of the work, means for moving the other member toward and from the yieldable member alternately to grasp the work for feeding and to release it, means for moving the yieldable member through a predetermined distance from the point at which the work positioned it in its yield, and means for moving the members together with the grasped work and in the opposite direction when said work is released.

5. In a rounding machine, a knife, opposite work-feeding members co-operating with the knife, means for imparting to the members their feeding movement, means for moving the members relatively to grasp the work, and means for withdrawing one of the members from the work, said withdrawing means being made effective as a result of the feeding movement of the members.

6. In a rounding machine, a knife, opposite work-feeding members co-operating with the knife, means for imparting to the members their feeding movement, means including a spring for moving the members relatively to grasp the work, and a cam for withdrawing one of the members from the work, said withdrawing means being made effective as a result of the feeding movement of the members.

7. In a rounding machine, a knife, opposite work-feeding members co-operating with the knife, means for moving the feeding members in opposite directions first to advance the work to receive the action of the knife and then to return them to their initial positions, means for producing relative movement of the members toward and from each other alternately to grasp the work for feeding and to release it during the return movement, means for producing a further movement of separation between the members, and a coupling device through which such further movement of separation is transmitted, said coupling device being disconnected by the movement of the members.

8. In a rounding machine, a knife, opposite work-feeding members co-operating with the knife, means for moving the feeding members in opposite directions first to advance the work to receive the action of the knife and then to return them to their initial positions, means for producing relative movement of the members toward and from each other alternately to grasp the work for feeding and to release it during the return movement, means for producing a further movement of separation between the members, and a coupling device through which such further movement of separation is transmitted, said coupling device being disconnected at the termination of the return movement of the members.

9. In a rounding machine, a knife, opposite work-feeding members co-operating with the

knife, means for moving the feeding members in opposite directions first to advance the work to receive the action of the knife and then to return them to their initial positions, means for producing relative movement of the members toward and from each other alternately to grasp the work for feeding and to release it during the return movement, means for producing a further movement of separation between the members, and a toothed member and engaging pawl through which said further movement of separation is transmitted.

10. In a rounding machine, a knife, opposite work-feeding members co-operating with the knife, means for moving the feeding members in opposite directions first to advance the work to receive the action of the knife and then to return them to their initial positions, means for producing relative movement of the members toward and from each other alternately to grasp the work for feeding and to release it during the return movement, an actuating member by which movement of release is produced, a toothed member movable by the actuating member, and a pawl carried by one of the feeding members for engagement with the toothed member.

11. In a rounding machine, a knife, opposite work-feeding members co-operating with the knife, means for moving the feeding members in opposite directions first to advance the work to receive the action of the knife and then to return them to their initial positions, means for producing relative movement of the members toward and from each other alternately to grasp the work for feeding and to release it during the return movement, an actuating member by which movement of release is produced, a toothed member movable by the actuating member, and a pawl carried by one of the feeding members for engaging and disengaging the toothed member during a portion of the movement of the feeding members.

12. In a rounding machine, a knife, opposite work-feeding members co-operating with the knife, means for moving the feeding members in opposite directions first to advance the work to receive the action of the knife and then to return them to their initial positions, means for producing relative movement of the members toward and from each other alternately to grasp the work for feeding and to release it during the return movement, means for producing a further movement of separation between the members, a movable toothed member and engaging pawl through which said further movement of separation is transmitted, and means arranged to vary the time at which the movement of the toothed member is initiated.

13. In a rounding machine, a knife, opposite work-feeding members co-operating with the knife, means for moving the feeding members in opposite directions first to advance the work to receive the action of the knife and then to return them to their initial positions, means for producing relative movement of the members toward and from each other alternately to grasp the work for feeding and to release it during the return movement, means for producing a further movement of separation between the members, a toothed member and engaging pawl through which said further movement of separation is transmitted, and means arranged to vary the normal relation between the toothed member and the pawl.

14. In a sole-rounding machine, a rounding knife, work-feeding members for engagement with opposite sides of a sole and co-operating with the knife, means for moving the members together to feed the work, means for moving one of the members to measure said work, and means for moving such member away from the work from a point determined by the measurement.

15. In a sole-rounding machine, a rounding knife, work-feeding members for engagement with opposite sides of a sole and co-operating with the knife, means for moving the members together to feed the work, means for forcing one of said members yieldably against the work, and means acting under the power of the machine for withdrawing said member positively from the work through a predetermined distance.

16. In a sole-rounding machine, a rounding knife, work-feeding members for engagement with opposite sides of a sole and co-operating with the knife, means for moving the members together to feed the work, a spring acting to force one of said members against the work, a movable cam, and means connecting the cam to the spring-actuated member in different positions of said spring-actuated member as determined by its engagement with the work.

17. In a sole-rounding machine, a rounding knife, work-feeding members for engagement with opposite sides of a sole and co-operating with the knife, means for moving the members together to feed the work, a spring acting to force one of said members against the work, a movable cam, means connecting the cam to the spring-actuated member in different positions of said spring-actuated member as determined by its engagement with the work, and means arranged to vary the time of action of the cam upon the connecting means.

18. In a sole-rounding machine, a rounding knife, work-feeding members for engagement with opposite sides of a sole and co-operating with the knife, means for moving the members together to feed the work, a spring acting to force one of said members against the work, a movable cam, means connecting the cam to the spring-actuated member in different positions of said spring-actuated member as determined by its engagement with the work, and means arranged to vary the point at which said connection will occur.

19. In a sole-rounding machine, a rounding knife, an oscillatory feed-plate and bottom-rest for engagement with opposite sides of a sole, an oscillatory member by which the bottom-rest is carried, a spring acting upon the member to force the bottom-rest toward the feed-plate, a rotatable cam, a rack, and a pawl engaging said rack, one of such engaging members being carried by the member and the other being movable by the cam.

20. In a sole-rounding machine, a rounding knife, an oscillatory feed-plate and bottom-rest for engagement with opposite sides of a sole, an oscillatory member by which the bottom-rest is carried, a spring acting upon the member to force the bottom-rest toward the feed-plate, a rotatable cam, a rack, and a pawl engaging said rack, one of such engaging members being carried by the member and the other being movable by the cam and separating during a portion of the oscillation of the member.

21. In a sole-rounding machine, a rounding knife, an oscillatory feed-plate and bottom-rest for engagement with opposite sides of a sole, an oscillatory sleeve by which the bottom-rest is

carried, a spring acting upon the sleeve to force the bottom-rest toward the feed-plate, a reciprocatory rack, a rotary cam, a lever movable by the cam and connected to the rack, and a pawl carried by the sleeve and engaging the rack.

22. In a sole-rounding machine, a rounding knife, an oscillatory feed-plate and bottom-rest for engagement with opposite sides of a sole, an oscillatory sleeve by which the bottom-rest is carried, a spring acting upon the sleeve to force the bottom-rest toward the feed-plate, a reciprocatory rack, a rotary cam, a lever movable by the cam and connected to the rack, and a pawl carried by the sleeve and movable into and out of engagement with the rack during the oscillation of the sleeve.

23. In a sole-rounding machine, a rounding knife, an oscillatory feed-plate and bottom-rest for engagement with opposite sides of a sole, an oscillatory sleeve by which the bottom-rest is carried, a spring acting upon the sleeve to force

the bottom-rest toward the feed-plate, a reciprocatory rack, a rotary cam, a lever movable by the cam, a gear oscillated by the lever, an arm extending from the gear and acting upon the rack, and a pawl carried by the sleeve and movable into and out of engagement with the rack during the oscillation of the sleeve.

24. In a sole-rounding machine, a rounding knife, an oscillatory feed-plate and bottom-rest for engagement with opposite sides of a sole, an oscillatory sleeve by which the bottom-rest is carried, a spring acting upon the sleeve to force the bottom-rest toward the feed-plate, a reciprocatory rack, a rotary cam, a lever movable by the cam, a gear oscillated by the lever, an arm extending from the gear and acting upon the rack, means arranged to fix the arm in different positions upon the gear, and a pawl carried by the sleeve and movable into and out of engagement with the rack during the oscillation of the sleeve.

JAMES P. FREDERICKSEN.
